COPY HOLDER

Howard D. Randall, Cincinnati, Ohio, assignor to
 The Randall Company, Cincinnati, Ohio, a corporation of Ohio

Application September 19, 1933, Serial No. 690,117

16 Claims. (Cl. 120—29)

This invention relates to a copy holder and has for an object the provision of such a device which may be extended to a height greater than that of the average copyholder, and yet which in its lowered position is adapted to be conveniently received and permanently positioned in a typewriter enclosing desk, the device being then about the same height as the ordinary typewriter.

Another object is to provide a copy holder of the kind described provided with a novel, simple and efficient operating means.

Another object is to provide a device of this kind having a new and efficient type of support for copy pages.

Another object is the provision of a copy holder of the kind set forth which is of simple and permanent construction and smooth and simple in operation.

These and other objects are attained by the means described herein and illustrated in the accompanying drawings, in which:

Fig. 1 is a front elevational view of the copy holder of this invention in its initial operative position.

Fig. 2 is a cross sectional view taken on line 2—2 of Fig. 1.

Fig. 3 is a rear elevational view of the copy holder in fully raised position.

Fig. 4 is a side elevational view, with parts broken away, of the encased ratchet mechanism and associated operating lever forming parts of the present invention, the said parts being disposed in their lowered or normal positions and the cover of the casing being removed.

Fig. 5 is a cross sectional view taken on line 5—5 of Fig. 4.

Fig. 6 is a fragmental view similar to Fig. 4 but showing the ratchet mechanism and lever at the limit of their upper movement by which movement the copy holder is adapted to be raised.

Fig. 7 is a fragmental side elevational view of the pressure rollers forming details of this invention and shown in their nonoperative or release positions.

Fig. 8 is a detail view of the bracket forming a part of the pressure roller mechanism.

Fig. 9 is an enlarged cross sectional view taken on line 9—9 of Fig. 3.

Fig. 10 is an enlarged cross sectional view taken on line 10—10 of Fig. 3.

Heretofore copy holders have been commonly constructed of two principal parts, namely, an immovable copy holder section and a movable

section adapted to be raised above the immovable section during use. Obviously to be adapted for extension to the height usually necessary during use of a copy holder, the sections of the devices such as described, have had to be of considerable height individually with the result that, even in lowered inoperative position, they were of such height as to extend a considerable distance above the ordinary typewriter, so that it was necessary to remove the copy holder from its operative position behind a typewriter when it was desired to close the typewriter enclosing desk.

These difficulties have been overcome by the present invention which provides for a copy holder comprising an extensible frame of telescopically associated parts which may be raised to a height greater than heretofore possible and yet, due to the telescopic structure, may be lowered to a nested or unextended position at which time the height of the device is no greater than that of the average typewriter so that the copyholder may be permanently retained in the typewriter enclosing desks now commonly utilized.

Another important feature of the present invention is the curtain-like support for copy pages which is drawn upwardly simultaneously with the extensible frame of the copyholder, and which, in its unextended position, occupies a minimum of space. In addition to this, the work support referred to is a highly desirable substitute for the heavy and unwieldy sheets of metal now commonly utilized in copy holders for supporting the copy pages. Other advantages and improvements are provided by the present invention and which will appear in the course of the following description.

In the drawings the copy holder is shown as comprising a base 12 of rectangular shape in plan and which may be provided with a narrow upturned flange 13 around the greater part of its periphery. An extensible frame is mounted on this base. The frame comprises a pair of parallel standards 14 and 15 each consisting of a plurality of telescopically associated tube sections, the respective tube sections of one standard being of substantially identical dimensions with the respective tube sections of the other standard. These tube sections are shown in extended relationship in Fig. 3 wherein each standard comprises the widest or lowermost pair of tube sections 16 and the succeeding pairs 17, 18, and 19 of progressively diminishing diameter. The lowermost pair 16 of tube sections may be

fixed to the base 12 by means of sleeves 20 and 21, each embracing the lower end portion of one of the tube sections 16 and having extending therebetween an integral rigid vertical wall 22. 5 Said sleeves and integral wall may be provided at the bottom with right angle flange portions adapted to be spot welded to the base 12 or secured in any suitable manner. The upper ends of said sleeves 20 and 21 are formed to provide 10 clamp portions 23 and 24, Fig. 3, adapted to embrace and be tightened about the pair of tube sections 16. It is obvious that the standards, by this means, may be readily mounted upon and removed from the base 12. The bottom 15 ends of each succeeding pair of tube sections extend some distance into the tube sections next below so as to preclude wobbling of the tube sections in their raised positions. In addition to this, the upper ends of the tube sections are constricted or "pinched" as at 25 so that each tube section will snugly embrace the next succeeding section. The tube sections are precluded from separation by means of small lugs 26 which are struck inwardly of the tube sections and the extreme lower ends of the removable tube sections are flared as at 27, Fig. 3, so as to strike against the inwardly projecting lugs 26 whereby further upward movement of the tube sections is precluded. 25

30 A top piece 28 extends transversely between the standards and is fixed adjacent each side to the innermost pair 19 of the movable tube sections. This top piece may be formed on its top and sides with rearwardly projecting flanges 29 and 30 and the tube sections 19 are secured to the top flange by projecting a headed pin 31, Fig. 3, downwardly through said flange into the upper ends of said tube sections 19, a set screw 32 being utilized for fixing the pin in place. For 35 further supporting and securing the upper ends of the tube sections 19, a pair of substantial V-shaped brackets 33, Fig. 3, is provided. Each tube section 19 passes through the midsection of one of the brackets 33 and the latter is formed 40 at its upper ends with outwardly projecting flanges 34 which are suitably secured such as by spot welding to the inner face of the top flange 29. Immediately beneath each bracket 33 a pair 45 of cushion washers 35 may be positioned about tube sections 19 to serve as shock absorbers when the tube sections are dropped to their nested relationship when said cushion washers are disposed immediately adjacent the tops of the lowermost tube sections 16. The top piece 50 50 is further provided with a clamp member 36, the cross bar 37 of which is urged into contact against the front face of top piece 28 whereby copy pages may be clipped to the copy holder. For retaining the upper portions of copy pages, a coil spring 38 may be attached to the upper face 55 of the top flange 29 of top piece 28.

The extensible frame just described is adapted 60 to have associated therewith a curtain-like support 39 adapted to support copy pages in proper position to be read. Said curtain-like member comprises a roll 40 of suitable sheet material, such as latex, which is wound about a spring roller 41 of the kind commonly utilized for window shade rollers. This roller 41 has its ends 65 mounted in brackets 42 and 43, Fig. 3, the inner ends of the brackets being clamped as at 44 to the fixed pair 16 of tube sections. The outer end of the sheet material 39 is attached to the top piece 28. For this purpose said outer end of the 70 sheet material has attached along its edge a

light metal binder 45. At the middle the binder has an aperture which is adapted to be engaged by a hook 46, Fig. 2, struck out from the lower portion of top piece 28. By these means the sheet material 39 may rapidly be removed from operative position when so desired. An eye guide 47 is hingedly associated with the upper ends of the fixed tube sections 16. This eye guide may consist of a suitable length of strip material extending transversely of the extensible 10 frame in front of the curtain-like work support described. Along its bottom edge the eye guide is turned upon itself at 48, Fig. 2, to form a journal through which extends the transverse portion 49 of a wire frame 50. Just behind the 15 eye guide strip 47 the wire frame 50 is bent inwardly at right angles to provide the bent sections 51, Fig. 3, about which suitable cushion sleeves 52 may be disposed. The lower ends of the wire frame 50 are again bent inwardly and 20 embraced by journal plates 53 which are secured to the ends of a transversely extending bar 54 secured to the upper ends of the fixed pair 16 of tube sections. This structure likewise is clearly seen in Fig. 3. It may be here remarked when 25 the wire frame 50 of the guide is turned up in the position seen in Figs. 2 and 3, the cushions 52 are adapted to limit downward or collapsing movement of the extensible frame at a point above the completely collapsed condition of the 30 frame. This limiting movement is effected by striking of the lower ends 300 of the lateral flanges 30 of said top piece 28 against the cushion members 52. This piece is seen in Fig. 35 and is the initial operative position of the 35 copy holder, that is to say, the position at which the top portions of copy pages are most conveniently visible. By further reference to Fig. 2 it will be obvious that the upper edge portions of copy pages are clipped beneath transverse bar 40 40 and the portion to be copied first will be seen by the operator immediately beneath said bar. Thereafter, as the work is copied, the copy pages, the extensible frame, and the sheet material 39 are progressively raised above the positioned eye 45 guide 47, all of which is well understood by those acquainted with the use of copy holders.

The progressive raising of the extensible frame is accomplished by novel means comprising a coil of steel tape 55. This tape is preferably 50 arcuate in cross section so that in extended position it possesses considerable rigidity. This kind of steel tape, as is well known, is adapted to be rolled flat and in the present instance is coiled within a casing 56 mounted on the base 12. 55 The tape is adapted to pass upwardly through an outlet 57 in the casing 56 and between a pair of pressure rollers, the outer end of the steel tape being fixed as at 58 to the top piece 28, that is to say, it may conveniently be fixed upon a block 59 depending from the inner face of the top flange 29 of said top piece. Means are likewise provided for precluding buckling of the extended tape so that when the latter is fed upwardly by the pressure rolls, the extensible frame as a whole is likewise raised, said means to be later described.

The pressure rolls referred to comprise a roller 60 having a convex periphery and mounted fixedly at the end of a shaft 61, Fig. 3, which 70 extends laterally of the extensible frame. The inner end of said shaft 61 is journaled in a suitable support plate 62 to which the tape casing 56 may likewise be conveniently secured, as at 63. The roller 60 and associated structure is 75

mounted at the rear of the vertical wall 22 here-
tofore mentioned (Fig. 2).

This wall 22, adjacent the middle, is provided
with an upward extension 64 which is aper-
tured in the middle for a purpose to be now de-
scribed. A second pressure roller 65 is mounted
to project through the aperture just mentioned
and to bear forcibly against the periphery of
the roller 60, that is to say, against the tape 55
which passes between these rollers. The roller
65 is of concave shape in its periphery to cor-
respond with the convex periphery of roller 60,
the rollers being thus adapted to snugly engage
the steel tape of arcuate cross section.

15 Roller 65 is provided with a short stud shaft 66
projecting laterally of the roller and which pro-
jecting portions are engaged by the upper ends
of a pair of spring strips 67 and 68. The upper
ends of said spring strips are hook shaped for
20 engaging the stud shaft 66. The spring strips
67 and 68 are held in place and urged against
the vertical wall 22 by means of a suitable
clamp 69 secured to said wall. The ends of stud
shaft 66 are likewise engaged at each side of
25 the roller by a U-shaped bracket 70, the ends
of which are formed to provide hook members
71 that embrace the ends of said shaft on the
opposite sides thereof from the journal members
of said spring strips (Fig. 2). The end edges of
30 the bracket 70 are straight as shown at 72 and
the bottom portions of the ends of the bracket
are rounded as at 73 to provide a pair of ful-
crum points or heels, the function of which will
be later described. The straight end edges 72
35 of the bracket are held against the flat face of
the wall extension 64 by the pressure of the
spring strips 67 and 68.

Extending transversely of the bottom of the
copy holder and substantially in a line with
40 the top of the vertical wall 22 is an elongated
arm 74 which is the primary means operative
upon the pressure rollers for releasing pressure
therebetween. Adjacent its middle, this arm is
formed with an extended portion shaped like a
45 bracket comprising the outwardly extending part
75, Fig. 2, and the vertically extending part 76
which projects upwardly in close proximity to
the outer face 77 of the bracket 70. At the top,
the vertical portion 76 is turned over to provide
50 a flange 78 which rests upon the top outer edge
79 of the bracket 70 and thereby holds the arm
74 in its normal position. The left end of arm
74, as seen in Fig. 1, is prevented from rising
upwardly during operation of the arm by means
55 of a small strip member 80 which overhangs
and slidably embraces the adjacent end of arm
74. The opposite end and adjacent portion of
the arm 74, as seen in Fig. 1, extends downwardly
60 at an angle and the extreme end portion 81
projects through a slot, Fig. 4, provided in a
support plate 83 secured at this end of the base
12. This end 81 of the arm 74 is adapted to co-
operate with the copy holder operating means
65 to be now described.

The means for controlling the copy holder
65 comprise a ratchet mechanism disposed in a
casing 82 fixed to the support plate 83 and pro-
vided on its outer side with a removable cover
84, Fig. 1. With reference to Figs. 4, 5, and 6,
the ratchet mechanism comprises a ratchet wheel
85 fixed upon the outer end of the shaft 61 here-
tofore described which shaft end projects
70 through and is journaled in the support plate 83
and the rear face of the casing 82. Behind the
75 ratchet wheel 85 a pivot plate 86 is rotatably

mounted upon the shaft 61 and at the upper left
hand corner of the pivot plate 86 an upper pawl
87 is pivotally mounted and urged by a spring
88 into engagement with the teeth of the ratchet
wheel. A spring 89 cooperating with the pivot
plate 86, urges the latter downwardly into con-
tact against a stop 90 projecting inwardly of the
casing. On the lower left hand corner of the
pivot plate 86, a stud member 91 is fixed, the
latter being formed adjacent its outer end with 10
an annular way 92, Fig. 1. A lower pawl 93 is
mounted in the casing beneath the ratchet wheel
85, being spring urged into engagement with the
teeth of said wheel and serving to preclude ro-
tation of the wheel in a counter-clockwise direc-
15 tion. Forwardly of the ratchet casing 82 a bifur-
cated fulcrum member 94 is fixed to the base 12
and has pivotally mounted between its upper
ends, as at 95, the operating lever 96 by which
the copy holder is raised and lowered. The in-
20 nner end of the lever 96 is bent as at 97 so as
to enter within the ratchet casing 82 through
slot 98 provided therein (Fig. 2). Said inner
end of the lever 96 is disposed beneath the stud
member 91 and is adapted to ride within the 25
groove 92 of said stud member.

When the outer end of the lever 96 is pivotally
moved downwardly by an operator, the inner
end bears against the stud member 91 and car-
ries the pivot plate 86 and upper pawl 87 up-
wardly in a clockwise direction to substantially
the position illustrated in Fig. 6 which repre-
sents the limit of this movement of the lever.
At the time of this movement, the pawl 87 en-
gages the ratchet wheel and rotates the latter 30
as well as the shaft 61 to which it is fixed.
This rotary movement is transmitted by the
shaft 61 to the rear pressure roller 60 and con-
sequently the tape 55, tightly engaged by its
pressure rollers, is fed upwardly upon each of 40
such movements of the lever. The spring 89
returns pivot plate 86 and the lever 96 to their
initial position, during which return movement,
the teeth of the upper pawl 87 merely ride or
45 slip over the teeth of the ratchet. In this man-
ner, the copy holder may be raised to the total
height of the extended tube sections, as illus-
trated in Fig. 3. To preclude buckling of the
extended tape, a series of telescopically associ-
50 ated channel members 99, 100, 101, 102 and 103
are provided. The lowermost and largest of
these channels is secured to the inner face of
the transverse bar 54 as by a suitable clamp 104,
Fig. 2. With reference to Figs. 9 and 10 it will
be seen that each channel member is of a nar-
row rectangular shape in cross section. At the
55 top of each of these channel members the end
portion thereof is constricted as seen at 105,
Fig. 9, while the lower end portion of the next
succeeding channel member is flared or dis-
tended to provide a shoulder as shown at 106,
so as to engage the portion 105 of the preceding
60 channel member whereby upward movement of
the various component parts of the structure is
limited. It will further be seen in Fig. 9 that
shoulder 106 is disposed a considerable distance
65 above the lower end of the channel member
with which it is associated so that the extreme
lower end portions of the channel members serve
to give rigidity to the anti-buckling device in its
extended position. The uppermost or innermost
70 channel member 103 has its upper end fixed as
at 107 to block 59 projecting downwardly from
the inner face of the top flange 29 of the top
piece 28, as previously described. 75

For lowering the extended copy holder, the outer end of the lever 96 is moved upwardly at which time its inner end bears down against the outer end 81 of the release arm 74 associated with the pressure rollers. At this time the flange 78 of the bracket member heretofore described as integral with the arm 74, carries the outer end of the bracket member 70 downwardly, that is to say, the member 70 is pivotally moved from the position seen in Fig. 2 to the position illustrated in Fig. 7. At this time the fulcrum portions 73 of the bracket 70 swing around into contact with the face of the wall extension 64 and thereby force the roller shaft 66 and roller 65 forwardly or out of snug engagement with the steel tape 55 and roller 60 whereby the tape is released and all the component parts of the elevated copy holder, including the tube sections, the anti-buckling means described and the extended sheet material for supporting the copy pages, return to their unextended position, the sheet material being rerolled by virtue of its spring roller and the other parts of the copy holder falling of their own weight into nested relationship. It should be here noted that when the copy holder is to be lowered into completely inoperative position, the eye guide frame 50 is lowered by forward hinged movement thereof so that the cushion members 52 will not limit downward movement of the top piece 28, whereby the various tube sections assume their most completely nested relationship with the tops of the tube sections disposed close together adjacent the tops of the lowermost or fixed sections 16. This relationship may be understood by reference to Fig. 2 wherein the nested relationship of all the tube sections except the innermost sections may be seen at 109. It will be seen in Figs. 1 and 2 that outward movement 40 of the operating arm 74 from the wall 22 is precluded by a suitable guide 108 attached to said wall by the same retaining means utilized for the spring arm clamp 69.

The device is readily assembled and disassembled and may be permanently positioned behind a typewriter in a typewriter enclosing desk, at which time the operating lever 96 extends forwardly and at the right hand side of the typewriter in a position to be conveniently manipulated by an operator.

What is claimed is:

1. A copy holder comprising a base, an extensible frame mounted on the base, said frame comprising a pair of standards consisting each of a plurality of telescopically associated tube sections, the respective tube sections of one standard being substantially identical with the like tube section of the other standard, the widest tube section of each standard being fixed 55 to said base, a top piece extending between said standards and secured at the sides to the innermost of said tube sections, a roll of sheet material attached to and extending transversely of said fixed tube sections and having its outer portion projecting upwardly and the adjacent end thereof attached to said top piece, the pages being adapted to depend and lie against the unrolled portion of said sheet material, a hingedly mounted strip positioned adjacent said 60 sheet material and adapted to extend transversely across the face of positioned copy pages, a pair of pressure rollers and a coil of steel tape mounted on said base, the tape passing upwardly between and engaged by said rollers 65 and having its outer end secured to said top

piece, means for turning one of said rollers to feed said tape upwardly and thereby raise said top piece and the associated tube sections, the copy pages at this time being carried upwardly behind said transversely extending strip whereby the latter serves as an eye guide, means to preclude buckling of the extended tape, means for holding the raised top piece and associated parts at any selected degree of elevation, and means for returning the raised frame and the extended tape and sheet material to their unextended positions. 5

2. A copy holder comprising a base, an extensible frame mounted on the base and adapted to have copy pages clipped to the top portion thereof, a pair of pressure rollers and a coil of steel tape mounted on the base, the tape passing upwardly between and engaged by said rollers and having its outer end secured to the top of said frame, means for turning one of said 10 rollers to feed the tape upwardly, means to preclude buckling of the extended tape whereby the latter carries the frame upwardly, means for holding the raised frame at selected degrees of elevation, and means to return the frame and 20 tape to unextended position. 20

3. A copy holder comprising a base, an extensible frame mounted on the base and adapted to have copy pages clipped to the top portion thereof, a coil of steel tape mounted on the base 30 and of arcuate cross section when extended, a pair of pressure rollers mounted on the base and formed, one with a convex and the other with a concave periphery for snugly engaging between them the extended tape, the latter passing upwardly between said rollers and having its outer end fixed to the top of said frame, means for turning one of said rollers to feed the tape upwardly, means for holding the extended tape in upright position whereby the frame is raised 35 by said upward feeding of the tape, means for normally precluding reverse turning of said rollers whereby the raised frame may be held at any desired degree of elevation, and means for releasing pressure between said rollers to effect 40 return of the tape and frame to unextended positions. 45

4. A copy holder comprising a base, an extensible frame mounted on the base and adapted to have copy pages clipped to the top portion thereof, a pair of pressure rollers and a coil of steel tape mounted on the base, the tape passing upwardly between and engaged by said rollers and having its outer end fixed to the top of said frame, a shaft fixed in and serving as the axis 50 of one of said rollers and projecting laterally of said frame, a ratchet associated with the laterally projecting end of said shaft and including a ratchet wheel fixed to said shaft end, a lever pivotally mounted on said base and co-operating with said ratchet wheel for turning the latter and the associated shaft and roller whereby said tape is fed upwardly, means to maintain the extended tape in upright position whereby upward feeding of the tape raises said frame, and means for releasing pressure between 55 said rollers to effect return of the tape and frame to unextended positions. 60

5. A copy holder comprising a base, an extensible frame mounted on the base and adapted to have copy pages clipped to the top portion 70 thereof, a pair of rollers mounted on the base, spring means urging the periphery of one roller toward the periphery of the other, a coil of steel tape mounted on the base, the tape passing 75

upwardly between and engaged by the peripheries of said rollers and having its outer end fixed to the top of said frame, means for turning one of said rollers to feed said tape upwardly, 5 means for maintaining the extended tape in upright position whereby upward feeding of the tape raises said frame, and means for releasing the spring pressure operative on said rollers and the tape engaged thereby to effect recoiling of 10 the tape and return of said frame to unextended position.

6. In combination, an upright wall, a roller rotatably mounted in a stationary position on one side of the wall, a pair of spring strips 15 positioned upright adjacent the opposite side of the wall, the upper ends of said strips being formed to provide a pair of journal members, a second roller provided with a stub shaft projecting laterally of each side of the roller, said 20 spring strip journals engaging opposite ends of said shaft and urging the roller toward said wall and through an aperture therein into peripheral contact with said first roller, a U-shaped bracket 25 embracing said second roller and having its end portions formed to provide hooks likewise engaging said stub shaft whereby the bracket is pivotally movable about said shaft, the extreme 30 ends of said bracket being straight and normally lying flush against the face of said wall, and the lower portions of said bracket ends being rounded to form a fulcrum portion, an arm extending transversely of said wall beneath said bracket, an 35 extension on said arm and frictionally engaging the outer end of said bracket, and lever means for urging said arm and its extension downwardly whereby said bracket is pivotally moved about said stub shaft and said fulcrum portion is turned upwardly against the adjacent face of said wall for urging the bracket outwardly and the associated roller out of pressure 40 relationship with said first roller, said spring strips, upon release of said lever means, effecting a return pivotal movement of the bracket to its initial position for restoring pressure relationship of the rollers.

45 7. In combination, an extensible member, a pair of pressure rollers positioned adjacent thereto, a coil of steel tape mounted adjacent the rollers, the tape passing between and engaged 50 by the rollers and having its outer end secured to the top of said extensible member, a series of telescopically associated channel members embracing the uncoiled portion of said tape, the outermost channel member being fixedly positioned immediately above said rollers and the innermost of said channel members having its 55 upper end fixed to the top of said extensible member, means to rotate one of said pressure rollers for feeding the steel tape upwardly, the channel members precluding buckling of the tape whereby the extensible frame is raised and the channel members telescopically extended, and means for returning the frame, tape and 60 channel members to unextended position.

65 8. In a copy holder the combination, with a support, of a copy holding member vertically extensible with respect thereto, a tape member also extensible from said support, operatively associated with said copy holding member, and means for extending said tape member with respect to said support, whereby the movement of 70 said tape member will be transmitted to said copy holding member.

9. In a copy holder the combination, with a

support, of a copy holding member vertically extensible with respect thereto, a tape member also extensible from said support, operatively associated with said copy holding member, and means for extending said tape member step by step with respect to said support, whereby the movement of said tape member will be transmitted to said copy holding member. 5

10. In a copy holder the combination, with a support, of a copy holding member vertically extensible with respect thereto, a tape member also extensible from said support, operatively associated with said copy holding member, and adjustable means for extending said tape member step by step with respect to said support, 15 whereby the movement of said tape member will be transmitted to said copy holding member.

11. In a copy holder the combination, with a support and a copy holding member vertically extensible with respect thereto, of a tape member 20 also extensible from said support, causing upward movement of said copy holding member.

12. In a copy holder the combination, with a support and a copy holding member vertically extensible with respect thereto, of a tape member 25 also extensible from said support, causing upward movement of said copy holding member, said tape member consisting of a spring metal strip, having a normally curved section imparting to it a certain rigidity, and being adapted 30 to yield to flattening action, causing the same to acquire flexibility.

13. In a copy holder the combination, with a support and a copy holding member vertically extensible with respect thereto, of a tape member 35 also extensible from said support, causing upward movement of said copy holding member, and a line indicator mounted on, and vertically adjustable with respect to said support.

14. In a copy holder the combination, with a support, of a copy holding member vertically extensible with respect thereto, a tape member also extensible from said support, operatively associated with said copy holding member, and unidirectionally operative means for extending 45 said tape member step by step with respect to said support, whereby the movement of said tape member will be transmitted to said copy holding member.

15. In a copy holder the combination, with a support, of a copy holding member vertically extensible with respect thereto, a tape member also extensible from said support, operatively associated with said copy holding member, and adjustable unidirectionally operative means for 55 extending said tape member step by step with respect to said support, whereby the movement of said tape member will be transmitted to said copy holding member.

16. In a copy holder the combination, with a support, of a copy holding member vertically extensible with respect thereto, a tape member also extensible from said support, operatively associated with said copy holding member, and unidirectionally operative means comprising an 60 actuating and an actuated member for extending said tape member with respect to said support, whereby the movement of said tape member will be transmitted to said copy holding member, said actuating member being releasable 65 so as to permit return movement of said actuated member. 70

HOWARD D. RANDALL.
